(57) **CLAIM**

The ornamental design for the beverage can, as shown and described.

DESCRIPTION

FIG. 1 is a front perspective view of a beverage can showing my new design, the rear perspective view being a mirror image;

FIG. 2 is a side elevational view thereof, the opposite side being a mirror image;

FIG. 3 is a top plan view thereof; and,

FIG. 4 is a bottom plan view thereof.

The broken line portions of the disclosure are for illustrative purposes only and form no part of the claimed design.

1 Claim, 2 Drawing Sheets

FIG. 1

FIG. 3

FIG. 2

FIG. 4
